Harold D. Remley ATTORNEY

UNITED STATES PATENT OFFICE

HENRY ADAMS, OF PLAINFIELD, NEW JERSEY, ASSIGNOR TO ADAMS COAL MACHINERY COMPANY, OF PLAINFIELD, NEW JERSEY, A CORPORATION OF CONNECTICUT

METHOD AND APPARATUS FOR STORING FLOWABLE SOLID MATERIAL

Application filed October 14, 1927. Serial No. 226,167.

This invention relates to methods and apparatus for storing flowable solid material and more particularly to means for filling bins, pockets or the like with coal or similar broken material and removing it therefrom, though it is noted that the invention is not limited to broken material or storing.

One object of the invention is to provide an apparatus and method of this kind where-
10 by material having fines and large pieces therein may be stored and later withdrawn with the fines and large pieces well mixed.

Another object of the invention is to pro-
15 vide a method of this kind for mixing the fines and the larger pieces.

Another object of the invention is to pro-
10 vide an improved combination of the apparatus shown in my United States Patents
Nos. 1,234,709 and 1,234,710 issued July 31,
20 1927, whereby coal or the like lowered into a bin by the latter may be withdrawn in a well mixed condition by the former, thus giving a new function not possible with either old apparatus.

25 Another object is to provide a convenient means for preventing the caking of the coal or the like by ice.

Other objects of the invention are to im-
30 prove generally the simplicity and efficiency of such methods and apparatus, to provide an economical and reliable method and to pro-
vide an apparatus of this kind which is eco-
nomical durable and reliable in operation, and economical to erect.

35 Still other objects of the invention will appear as the description proceeds; and while herein details of the invention are de-
scribed and claimed, the invention is not lim-
ited to these, since many and various changes
40 may be made without departing from the scope of the invention as claimed in the broader claims.

The invention features for the accom-
45 plishment of these and other objects are shown herein in connection with an improved coal handling method which, briefly stated, in-
cludes gradually lowering the coal or other flowable solid material to form a pile having fines therein adapted to sink near the point
50 of lowering, many of the larger pieces roll-

ing or otherwise moving over the pile to points more or less remote from the fines where the material is confined, as by bin walls, remote from the fines to build up a confined body.

The material is withdrawn at an outlet
beneath said fines and limited in its with-
drawal to a column over said outlet, whereby
material is fed to the column from all along
the top only of the body, as in said first
named patent, thereby bringing the large
pieces back to the fines and mixing them
with the fines on withdrawal.

While the method may be performed by
other apparatus than the one shown, I pre-
fer to perform it with the herein described
apparatus, which briefly stated includes a
vertical filling chute in said bin, said chute
having an unclosed side where the material
flows out and piles up, the fines sinking and
the large pieces rolling to points remote from
said unclosed side. Said bin is provided with
an out-let opening adjacent to said unclosed
side; and widely spaced uprights on the edge
of said opening define a vertical delivery
chute adjacent to said side for limiting the
withdrawal of material to a column over said
outlet, whereby material is fed to the column
from all along the top only of the body, as
in said first named patent, thus mixing the
large pieces with the fines as the material is
withdrawn.

In the accompanying drawing, showing by
way of example, one of many possible em-
bodiments of the invention,

Fig. 1 is a central longitudinal vertical sec-
tional view, partly in elevation, showing the
coal being withdrawn from the apparatus;

and
Fig. 2 is a plan of the apparatus.

The storage bin or pocket for the coal, coke
and other brittle or flowable solid material,
comprises vertical walls 10, 11, 12 and a floor
13, on which rests a vertical filling chute 15
near the mid part of one wall 10.

Said chute comprises opposite side walls
18, the adjacent side 10 of the bin serving as
an intermediate rear wall co-operating with
the side walls 18 to form three permanently
closed sides of the chute and leaving an un-

closed side 19 at all times substantially unclosed from top to bottom of the chute. A hopper 20 is formed at the upper end of the chute between said side walls 18.

- 5 Downwardly and inwardly inclined separate staggered baffles 22 are secured between said side walls 18 perpendicular thereto in vertical series to form a telegraph chute in said filling chute and extending substantially 10 from top to bottom of the filling chute and from said rear wall to the open side, an intermediate part of each baffle being beneath and spaced from the lower edge of the baffle just above, thereby to form a flowage space for 15 lowering the material from said hopper 20, in a column from the top to the bottom of the filling chute, without excessive breakage.

The floor 13 is provided with a square main outlet opening 22 adjacent to said unclosed 20 side 19 and a coarse material delivery opening 23 near the middle part of the opposite bin wall 11, the outlet openings being controlled by slide gates 24.

Vertical uprights or corner pieces 25, 26 of 25 right-angular cross-section, are mounted on the respective corners of said delivery opening 22, two of the corner pieces 26 being adjacent to the edge of said side walls 18 at said unclosed side 19. Said corner pieces co-operate to define a vertical delivery chute 27 open at every side entirely from end to end and extending from the delivery opening substantially to the top of the bin, one open side being adjacent to and co-extensive with the 35 unclosed side 19 of the filling chute.

As the material is lowered, said baffles 22 permit the material to pile up, first beneath the filling chute and then to overflow the baffles at the unclosed side into the discharge 40 chute, as long as material is supplied to the hopper and until the major portion of the bin and the delivery chute 27 is filled, the fines sinking in and near the delivery chute, the large pieces generally rolling or otherwise 45 moving to more or less remote parts of the bin.

The corner pieces 25, 26 form barriers limiting the portion of coal being delivered to an upright column as at 28, downwardly gravitationally moving without breakage and grinding in free contact at one side with coal at the unclosed side 19 of the delivery chute and at the other sides 29 with the main body of material, upon the top only of which column 28 as the column descends, fresh material including said large pieces from all along the top layer 30 of the main body is fed with a minimum of degradation at a slanting angle of about 25 to 30 degrees. This top 55 layer mixes with the fines nearer and at the column 28 as the material is withdrawn, to substantially the same proportion in which they were delivered to the bin.

The parts of said material below the top 60 layers 30 and adjacent to the open sides 29

automatically form a horizontally outwardly arched barrier, as indicated at the dotted line 31 and shown in said first named patent, preventing the flow of the main body into the column except at the top, whereby degrading 70 disturbance, grinding and breakage of the main body are prevented.

The mixed material is removable through said opening 22 controlled by the slide gate and is held against injurious fall and under 75 control from said hopper 20 to said gate by means of the gate, barriers, chutes and baffles, whereby degradation is reduced to a minimum.

The operation will be understood from the 80 foregoing, and need now be only briefly summarized as follows:

The coal or other material to be stored is received by the hopper 20 and baffled and gradually lowered by the baffles 22, the walls 85 10 and 18 confining the material in a narrow upright enclosure permitting it to discharge at said unclosed side 19 to form a pile having its highest part at said side. The fines are deposited near and at said unenclosed 90 side, the large pieces rolling over the pile, thereby to build up a confined body of the material ready to be withdrawn.

The fines in the column 27 are first withdrawn through the outlet 22 and separately 95 disposed of, the corner pieces 25, 26 limiting the withdrawal to an upright column over said outlet in contact throughout three sides 29 with the main body. This causes the top layer 30 only of the material to be fed to 100 the top of the column 28, mixing the large pieces with the fines adjacent to the column as the top layer moves to the column. The gate 24 holds the material in said outlet 22 under control, thereby controlling the entire 105 course of the material.

If material comprising mostly larger pieces be desired, it may be withdrawn through the opening 23.

Heating means is provided for preventing 110 material when wet from being caked up with ice; and this means which may be conveniently placed near the delivery column is here shown as comprising a pair of heating coils 35 having vertical heating members 36, 37, 115 upper members 38 connecting the heating members of each coil, and lower connecting members 39 respectively connected to opposite ends of the coil beneath the floor 13. Supply and discharge pipes 40 are connected 120 to said lower members 39 respectively whereby heating medium can be circulated through the coils to prevent the material when wet from being caked by ice. The heating members 36, 37 are secured in the angles of the 125 corner members for protecting and bracing the heating members, though it is noted that the invention is not limited to their location. The coils may be either pipes or electric conductors.

I claim as my invention:

1. In combination, a bin for flowable solid material; a vertical filling chute extending substantially to the bottom of said bin having an unclosed side where the material flows out and the fines sink the large pieces moving to points remote from said side; said bin having an outlet opening adjacent to said side; widely spaced pieces on the edge of said opening to define a vertical delivery chute adjacent to and communicating with said side for limiting the withdrawal of material to a column over said outlet, whereby material is fed, to the column, from all along the top only of the body, thus mixing the large pieces with the fines as the material is withdrawn. 10
2. In combination, a bin for flowable solid material, comprising side walls and a floor; a vertical filling chute near the mid part of one side of the bin comprising side walls and an intermediate wall one side being substantially unclosed from top to bottom; means for gradually lowering the material in said filling chute; said floor having a rectangular opening adjacent to said unclosed side; vertical corner pieces on the corners of said opening to define a vertical delivery chute open adjacent to said unclosed side. 20
3. In combination, a bin for flowable solid material, comprising side walls and a floor; a vertical filling chute near the mid part of one side of the bin comprising side walls and an intermediate wall one side being substantially unclosed from top to bottom; means for gradually lowering the material in said filling chute; said floor having a rectangular opening adjacent to said unclosed side; vertical corner pieces on the corners of said opening to define a vertical delivery chute open adjacent to said unclosed side; said material overflowing at the unclosed side into the delivery chute until the major portion of the bin is filled, the fines sinking in and near the discharge chute, the large pieces moving to remote parts of the bin, said pieces limiting the material being delivered to column, downwardly moving in free contact at one side with coal of the filling chute and at the other sides with the main body, the top only of which column fresh material including said large pieces from top layer of the main body is fed and mixed with the fines; said material below the top adjacent to the open sides forming a barrier preventing flow into the column except at the top. 30
4. In combination, a bin for flowable solid material, comprising a floor having a rectangular opening therein; vertical corner pieces of right angular cross-section on the corners of said opening to define a vertical delivery chute over said opening; a pair of heating coils having vertical heating members, upper members connecting the heating members of each coil, and lower connecting members respectively connected to opposite ends of the coils beneath the floor; supply and discharge pipes connected to said lower members respectively whereby heating medium can be circulated through the coils to prevent the material when wet from being caked by ice; said heating members being placed in the angles of the corner members for protecting and bracing the heating members. 70
5. In combination, means for holding flowable solid material in a single mass; a filling device for depositing material in said means; said means having an outlet opening near the point of deposit of the material and smaller than a downward projection of said mass; and widely spaced uprights near the edge of said opening to define a substantially vertical delivery chute laterally open to said mass. 75
6. In combination, a bin for flowable solid material; a vertical filling chute in said bin having an unclosed side extending substantially to the bottom of the bin; said bin having an outlet opening adjacent to said side; widely spaced uprights on the edge of said opening to define a vertical delivery chute adjacent to and communicating throughout with said side. 80
